US00D610784S

(12) United States Design Patent
Del Biondi

(10) Patent No.: US D610,784 S
(45) Date of Patent: * Mar. 2, 2010

(54) FOOTWEAR

(75) Inventor: Stefano Del Biondi, Noventa Padovana (IT)

(73) Assignee: Crocs, Inc., Niwot, CO (US)

() Term: 14 Years

(21) Appl. No.: 29/342,331

(22) Filed: Aug. 21, 2009

(30) Foreign Application Priority Data

Feb. 23, 2009 (EM) 001092258

(51) LOC (9) Cl. 02-04

(52) U.S. Cl. D2/916; D2/923; D2/926

(58) Field of Classification Search ..... D2/896, D2/898, 899, 900, 903, 916, 919-923, 926, D2/943, 969, 972; 36/45, 11.5, 8.1, 77 M, 36/77 R, 83, 113, 144, 116, 126-131, 3 B, 36/3 A

CLAIM

The ornamental design for footwear, as shown and described.

DESCRIPTION

FIG. 1 is a front perspective view.

FIG. 2 is a front view.

FIG. 3 is a back view.

FIG. 4 is an inner side view.

FIG. 5 is an outer side view.

FIG. 6 is a top view; and,

FIG. 7 is a bottom view.

The broken line showing of the sole, upper, and strap is for illustrative purpose only and forms no part of the claimed design.

1 Claim, 7 Drawing Sheets
